AIR FRESHENER

Andre G. Labrecque, 4946 Coolbrook Ave.,
Montreal 248, Quebec, Canada

Filed June 8, 1970, Ser. No. 23,380

Claims priority, application Canada Jan. 5, 1971

Term of patent 14 years

Int. Cl. D23—99

U.S. Cl. D23—150

FIG. 1 is an elevational view of the air freshener showing the new design; and

FIG. 2 is a side elevation thereof. The side opposite that shown in FIG. 1 is flat and unornamented. The supporting cord is shown in broken lines in FIG. 1 for illustrative purposes only.

I claim:

The ornamental design for an air freshener, as shown and described.
